(57) **CLAIM**

The ornamental design for a floor lamp as shown and
described.

DESCRIPTION

FIG. 1 is a perspective view of a floor lamp in a first state
showing our new design;

FIG. 2 is another perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom plan view thereof;

FIG. 9 is an enlarged view of a portion 9 of the floor lamp
shown in FIG. 2;

FIG. 10 is an enlarged view of a portion 10 of thereof shown
in FIG. 3;

FIG. 11 is an enlarged view of a portion 11 of thereof shown
in FIG. 4;

FIG. 12 is an enlarged view of a portion 12 of thereof shown
in FIG. 5;

FIG. 13 is an enlarged view of a portion 13 of thereof shown
in FIG. 6;

FIG. 14 is a first perspective view of the floor lamp in a
second state;

FIG. 15 is a second perspective view of thereof in the second
state;

FIG. 16 is a first view of the floor lamp in a third state;

FIG. 17 is a second perspective view of thereof in the third
state;

FIG. 18 is a perspective view of the floor lamp in a fourth
state; and,

FIG. 19 is another perspective view of thereof in the fourth
state.

The regular dash-dot lines are included for the purpose of
illustrating portions of the floor lamp that form no part of the

(Continued)

claimed design. The dot-dot-dash broken line defines the boundary of the enlarged views and form no part of the claimed design.
